UNITED STATES PATENT OFFICE.

DAVID BASCH, OF NEW YORK, N. Y.

DESIGN FOR A BICYCLE TOE-CLIP.

SPECIFICATION forming part of Design No. 28,478, dated April 12, 1898.

Application filed October 8, 1897. Serial No. 654,593. Term of patent 7 years.

To all whom it may concern:

Be it known that I, DAVID BASCH, a citizen of the United States, residing at New York city, in the county and State of New York, have invented and produced a new and original Design for a Bicycle Toe-Clip, of which the following is a specification, reference being had to the accompanying drawing, forming a part of this specification, in which is shown a perspective view of a bicycle toe-clip embodying the features of my design.

The design relates to toe-clips for bicycles having a body portion B, a drop member C, and a toe-piece D; and the intent of the design is to materially reshape that portion of the clip which is to connect with the pedal.

To that end the leading feature of the design consists in a toe-clip of the character described having the hook extensions A at the rear of the body portion and projecting beyond the drop member C. 20

A minor feature of the design consists in the openings a', which appear in the drop member C adjacent to the hook extensions A.

I claim—

The design for a bicycle toe-clip herein shown and described. 25

DAVID BASCH.
